(57) **CLAIM**

The ornamental design for a modular spa chair, as shown and described.

DESCRIPTION

This application is related to application Ser. No. 29/722,624, application Ser. No. 29/722,632, and application Ser. No. 29/722,656, all of which are concurrently filed herewith and entitled Modular Spa Chair, and the disclosures all of which are incorporated herein by reference.

FIG. 1 is a front perspective view of a modular spa chair according to our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a rear perspective view thereof.

The broken lines shown in the drawings are for the purpose of illustrating portions of the modular spa chair, which form no part of the claimed design.

1 Claim, 6 Drawing Sheets
